COMBINED BATHTUB AND WATER HEATER

Filed July 5, 1928

UNITED STATES PATENT OFFICE.

JOHN V. GARCIA, OF LOS ANGELES, CALIFORNIA.

COMBINED BATHTUB AND WATER HEATER.

Application filed July 5, 1928. Serial No. 290,335.

This invention relates to improvements in combined bath tubs and water heaters.

The general object of the invention is to provide a receptacle having means built 5 therein for heating water contained in the receptacle.

Another object of the invention is to provide a receptacle having a novel electric or gas heating means built therein.

10 Other objects and the advantages of this invention will be apparent from the following description taken in connection with the accompanying drawing wherein:

Fig. 1 is a perspective view of a bath tub embodying the features of my invention.

Fig. 2 is an enlarged cross section of the bath tub.

Fig. 3 is an enlarged section taken on line 3—3 of Fig. 2.

20 Fig. 4 is a side view of a bath tub embodying a modified form of heater.

Fig. 5 is a section taken on line 5—5 of Fig. 4, and

Fig. 6 is an enlarged section taken on line 25 6—6 of Fig. 5.

Referring to the drawing by reference characters I have indicated a bath tub embodying the features of my invention generally at 10. Although in the accompanying 30 drawing I have shown my invention in connection with a bath tub I wish it to be understood that it may be used in connection with various other receptacles with equal success.

The bath tub 10 may be of any type or 35 shape including side walls 12. Adjacent the bottom of each of the side walls 12 I provide an outwardly extending portion 14 having end walls 15 which form a chamber 16 on the inside of the tub. Each of the end 40 walls 15 of each portion 14 is provided with a screw threaded aperture 17 in which similarly screw threaded ends of a pipe 18 are positioned and retained in place by nuts 19 which engage the threads on the pipe and 45 bear against packing washers 20 interposed between the tub ends and the nuts.

Within the pipe 18 I position an electrical 50 heating element 21. As shown this heating element comprises a body portion 22 which may be made of vulcanized fibre or other material which is a non-conductor of electricity. In this body coiled resistance wires 23 are moulded. At one end of the element 21 the wires 23 are connected to a plug

socket 24 which extends out through one 55 end of the pipe 18 and is adapted to receive the prongs of a connector plug 25 connected by a cable 26 to an electric outlet fixture 27 as shown in Fig. 1. The end of the pipe 18 opposite the plug socket 24 is preferably 60 closed in any suitable manner as by a screw threaded pipe plug 28.

When it is desired to heat a tub of water the water is run in until the water level is above the chambers 16 and then the electric 65 current is switched on to heat the elements 21 which in turn heat the pipes 18 and thence the water in the tub.

In Figs. 4, 5 and 6 I have shown one arrangement wherein a fluid burner is adapted 70 to heat the pipe 18 and thence the water in the tub. Various types of fluid burners may be used but in the accompanying drawing I have shown a gas burner 30. As shown the gas burner 30 comprises a flame 75 pipe 31 having a plurality of apertures 32 therein and closed at one end as by a pipe cap 33. The opposite end of the pipe 31 engages a mixing valve 34 having a shut off valve 35 connected thereto to which a gas 80 hose 36 is attached.

The flame pipe 31 is adapted to be supported in the pipe 18 by a spider 37 secured to the pipe 31 and by a hub 38 on the mixing valve 34. The spider 37 and the mixing 85 valve hub 38 are adapted to be movable in the pipe 18 so that when it is desired to light the burner the burner is moved out of the end of the pipe 18 a short distance, the gas turned on and ignited and the burner moved 90 back to position within the pipe 18.

The end of the pipe 18 opposite the mixing valve 34 instead of being closed by the pipe plug 28 as in the case of the electrical 95 heater, has a pipe 40 connected thereto which is inclined downwardly towards the tub drain 41 and connected to the drain as shown in Figs. 4 and 5, thus affording a circulation of air for the burning gas.

Instead of connecting the pipes 40 to the 100 drain pipe 41 they may be connected to a chimney or any other suitable vent.

From the foregoing description it will be apparent that I have provided a novel water heater which is simple in construction, durable, and highly efficient in use.

Having described my invention, I claim:

1. A bath tub including side walls and

having a chamber in one of said side walls, a heating member in said chamber and means to heat said heating member.

2. The combination of a receptacle including a side wall having a chamber open to the interior of said receptacle, a pipe secured in said chamber and a fluid heating element associated with said pipe.

3. The combination of a receptacle including a side wall, an outwardly extending portion in said side wall, said outwardly extending portion forming a chamber open to the interior of said receptacle, a pipe arranged in said outwardly extending portion and a heating member arranged in said pipe.

4. In combination with a receptacle including side walls, an outwardly extending portion in opposite side walls, said outwardly extending portions forming chambers open to the interior of said receptacle, a pipe removably secured in each of said outwardly extending portions and a fluid heating element associated with each of said pipes.

5. In combination with a liquid container including side walls and having a drain leading therefrom, an outwardly extending portion in opposite side walls, said outwardly extending portions forming chambers open to the interior of said container, a pipe removably secured in each of said outwardly extending portions, fluid burning heaters, said heaters each being associated with one of first mentioned pipes and one end of each of first mentioned pipes having a conduit connected thereto and communicating with said drain.

6. In combination with a liquid container including side walls and having a drain

leading therefrom, an outwardly extending portion in one of said side walls, said outwardly extending portion forming a chamber open to the interior of said container, a pipe removably secured in said outwardly extending portion, a fluid burning heater associated therewith, said heater including a flame pipe, a mixing valve and a shut off valve, said flame pipe being adapted to be positioned in first mentioned pipe and coaxial with first mentioned pipe, the end of first mentioned pipe opposite to mixing valve having a conduit connected thereto and communicating with said drain.

7. In combination with a liquid container including side walls and having a drain leading therefrom, an outwardly extending portion in opposite side walls, said outwardly extending portions forming chambers open to the interior of said container, a pipe removably secured in each of said outwardly extending portions, fluid burning heaters associated therewith, said heaters including a flame pipe, a mixing valve and a shut-off valve, said flame pipes being positioned in first mentioned pipes, a spider on each flame pipe and a hub on each mixing valve adapted to support said flame pipe coaxial with one of first mentioned pipes, said spider and said hub being movable in first mentioned pipes and said hubs each being adapted to close one end of each of first mentioned pipes, the opposite ends of first mentioned pipes having a conduit connected thereto and communicating with said drain.

In testimony whereof, I hereunto affix my signature.

JOHN V. GARCIA.
